UNITED STATES PATENT OFFICE.

WILLIAM HENRY HOWARD, OF NEW YORK, N. Y., ASSIGNOR OF ONE-HALF
TO LEONARD W. SWEET AND ELI P. ELLSWORTH, OF SAME PLACE.

CHECK OR SIMILAR INSTRUMENT.

SPECIFICATION forming part of Letters Patent No. 599,842, dated March 1, 1898.

Application filed July 13, 1897. Serial No. 644,466. (No model.)

To all whom it may concern:

Be it known that I, WILLIAM HENRY HOWARD, a citizen of the United States, residing at New York, in the county and State of New York, have invented certain new and useful Improvements in Checks or other Similar Instruments, of which the following is a specification.

My invention relates to a system of negotiable instruments formed and designed in such a manner as to prevent fraud or alteration of an original instrument or issue, adapting the same to certain specified limitations and amounts, said limitations and amounts running in series, each series having its own insignia or earmark whereby it can be readily and instantly recognized as an instrument whose money value is within certain predetermined limitations.

20 In carrying out my invention I prefer to employ, and I have so shown in the accompanying drawings, which form a part of this specification and to which I shall specifically refer, a series of four different forms to accommodate my system to United States monies and values, although in this respect my invention may lend itself to other methods and values, and I do not limit myself to the exact means and devices shown, my idea and 25 system being the securing of a series, each member of the series lying within certain predetermined limits of value and each member also lending itself to means for fixing its exact value with certain possible and slight variations therefrom, and also being formed in such a manner that what is known in the commercial world as "raising" the value of an instrument is rendered absolutely impossible.

30 Referring to the accompanying drawings, Figures 1, 2, 3, and 4 show a series of checks embodying my present invention.

In an application filed by me on June 15, 1897, Serial No. 640,816, I have shown and 35 described a bank-check such as is illustrated in present Fig. 1, and in said application I have claimed the specific structure of the individual check, and in my present application I illustrate the variations of said invention 40 which may be employed in the system or series so as to accommodate or embrace larger

values. The check described and claimed in said application has a diagram lying within the area of the check and composed of two corresponding parts, each formed by lines and 45 intervening spaces radiating from a common point and each of said parts being in the form of a triangle so arranged with respect to one another that in order to designate the desired value the diagram may be severed 50 along intersecting lines running through both parts of the diagram and at an angle to each other.

In Fig. 1 I show a check which may be used for amounts ranging from one dollar or less 55 to ninety-nine dollars. This series I designate "Series A."

In Fig. 2 I show a check usable for amounts ranging from one hundred dollars to nine hundred and ninety dollars. This series I 60 designate as "Series B."

In Fig. 3 I have illustrated "Series C," ranging from one thousand dollars to nine thousand and nine hundred dollars, and in Fig. 4 I have illustrated "Series D," ranging from 75 ten thousand dollars to ninety-nine thousand dollars.

One means of distinguishing the different numbers of the series one from the other is the employment of the letters "A B C D," each 80 letter distinguishing the limitation of the check, without specifying its exact amount; but the more exact distinguishing feature is by means of the radiating lines L shown at the left-hand end of the check and within 85 the check proper. In "Series A" these radiating lines L radiate from a point P. In the form of "Series A" these lines have a base-line S at right angles to the longer edges or length of the check. In "Series B" the 90 base-line S runs from the lower edge of the check in such position as to make the lower left-hand corner of the check an obtuse angle and from the upper edge of the check in such position as to make the upper left-hand corner of the check an acute angle, which positions are reversed in "Series C." In "Series D" the base-line S is bent at the point P and is arranged at an acute angle at both the upper and lower edges of the check. By this 100 means the drawer of a check or draft or other instrument can, by employing such a series,

easily determine which of the forms to use according to the amount for which the instrument is to be drawn or made.

In the application above referred to I have 5 explained specifically the method of using this particular kind of check or draft, and my present application is only an enlargement and expansion of the idea therein shown and claimed—that is to say, I have applied the 10 invention in such a manner that it can be used in a series.

It will be seen that these checks have the same advantages as the check above referred to in that the non-raisable-value-designating 15 feature runs into the body of the instrument proper and that therefore the value-marks cannot be removed without such a mutilation of the check as would render it plainly valueless.

Having thus described my invention, what 20 I claim, and desire to secure by Letters Patent, is—

A series of checks or similar orders each having a diagram lying within the area of the check and composed of two corresponding parts formed of lines and intervening spaces which radiate from a common point, whereby in order to denote value, the diagram may be severed along two intersecting lines; the parts of the diagram being in the forms of 25 triangles having base-lines S, and said base-lines varying in positions in the respective forms of the series, in substantially the manner explained and for the purpose set forth.

WILLIAM HENRY HOWARD.
